(57) **CLAIM**

The ornamental design for a pan, as shown and described.

DESCRIPTION

The patent or application file contains at least one drawing executed in color photograph. Copies of this patent or patent application publication with color photograph(s) will be provided by the Office upon request and payment of the necessary fee.

FIG. 1 is a photographic perspective view of the pan;

FIG. 2 is photographic front view thereof;

FIG. 3 is a photographic rear view thereof;

FIG. 4 is a photographic right side view thereof;

FIG. 5 is a photographic left side view thereof;

FIG. 6 is a photographic top view thereof;

FIG. 7 is a photographic bottom view thereof; and,

FIG. 8 is a photographic right side view of the pan of FIG. 1 positioned over a gas stove burner, which is shown in broken lines.

The elements depicted in broken lines in the various figures are included for environmental purposes only, and form no part of the claimed design.

**1 Claim, 8 Drawing Sheets
(8 of 8 Drawing Sheet(s) Filed in Color)**

Related U.S. Application Data

continuation-in-part of application No. 29/547,842, filed on Dec. 8, 2015.
